COMBINED VALET STAND AND SEAT

Roger E. Davis, Traverse City, Mich., assignor to The Setwell Company, Traverse City, Mich., a corporation of Illinois

Filed Dec. 29, 1964, Ser. No. 83,544

Term of patent 14 years

(Cl. D33—8)

This application is a continuation-in-part of my earlier filed case Serial No. D. 77,452, filed November 18, 1963 and now abandoned.

I claim:

The ornamental design for a combined valet stand and seat, as shown and described.
